CLAIM

The ornamental design for a carrier for beverage container, as shown and described.

DESCRIPTION

FIG. 1 is a top, front and right side perspective view of a carrier for beverage container showing my new design; FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dotted lines in FIGS. 1-8 show stitching and form no part of the claimed design. The dashed lines in FIG. 7 show portions of the carrier for beverage container and form no part of the claimed design.

1 Claim, 8 Drawing Sheets
